FIRE FIGHTING NOZZLE

Filed Aug. 18, 1949

UNITED STATES PATENT OFFICE

2,542,014

FIRE FIGHTING NOZZLE

Theodoric B. Edwards, Hybla Valley Farms, and
Arthur L. Donaew, Alexandria, Va.

Application August 18, 1949, Serial No. 111,066

6 Claims. (Cl. 169—15)

(Granted under the act of March 3, 1883, as
amended April 30, 1928; 370 O. G. 757)

1

The invention described herein may be manufactured and used by or for the Government for governmental purposes, without payment to us of any royalty thereon.

For the combating of fires produced from the combustion of inflammable chemicals, oils, and other materials not affected by water, the use of foam-producing compositions for producing an air-excluding blanket around such fires is well known. Various compositions of such fire foam-producing materials are available for fire-extinguishing purposes, the compositions producing a liquid foam that envelops a mass of burning material and, by blanketing the fire from access of air, quickly smothers and extinguishes the same.

The use of such foams is of particular advantage where fires occur in locales where a vigorous application of extinguishing liquids may cause a scattering or spreading of the combustible material, which is true in cases where the combustible material is liquid and of less specific gravity than water and immiscible therewith, or where the combustible material is collected in large volume or in pools thereof. Also it is desirable to use a foam or spray where the fire-fighting personnel is in close quarters to the blaze, or where the blaze is intensely hot in character, and it is desirable to protect the personnel with a screen or blanket of the liquid material as a cooling spray, interposed between the personnel and the blaze being extinguished. In other instances, however, it may be necessary or desirable to combat a fire with extinguishing liquid directed thereon in solid streams.

Consequently, it is frequently desirable to have available fire-fighting equipment which will produce either a spray or a solid stream of extinguishing liquid, selectively.

This invention has for one of its objects the provision of a piece of equipment which preferably and conveniently may be an auxiliary attachment connectable to a standard or commercial nozzle for delivering a selected type of discharge of extinguishing liquid from the nozzle, which discharge may be either mechanical foam or a solid straight stream of the said liquid, selectively, the construction of the invention being adapted for use in conjunction with any of the usual foam-stabilizing agents.

Further objects of the invention will become apparent as the description proceeds and the features of novelty will be pointed out in particularity in the appended claims.

The invention will be understood more clearly

2

from reference to the accompanying drawings in which:

Fig. 1 is a sectional elevation of the construction of the present invention the view showing the embodiment of the invention attached to a commercial nozzle, which is shown partially in section; and

Fig. 2 is a sectional perspective view of the device of Fig. 1.

Referring more particularly to the drawings, the attachment of the present invention is represented by the illustrative embodiment A which is threadedly mounted on a nozzle B of standard commercial construction, which is secured to a hose line at C.

The attachment A forms an auxiliary nozzle and includes a housing 3, which includes an intake section D, a conical baffle section E and a perforated conical discharge section F.

The intake section D has its intake end closed by a closure 5 provided with a collar 7, the closure 5 and collar 7 being internally threaded at 8 to engage with the threads 9 on the nozzle B. The collar 7 receives a locking screw 10 and the tubular cylindrical housing 11 is secured to the closure 5 by screws 13. Also fixedly secured to the housing 11 of the intake section D by rivets or equivalent fastening means 14 are spaced webs 15 which are attached to the outer periphery of the housing 11 by the said rivets, as shown, and to the housing 3 of the attachment by suitable screws 17, the webs 15 having oppositely disposed flanges 19, 21 for receiving the fastening instrumentalities 14 and 17.

The intake section D opens into the frusto-conical baffle and mixing section E, which converges in the direction of the flow of liquid. The mixing section E includes a frusto-conical baffle and mixing housing 23 having a cylindrical portion 25 adjacent to its larger end for attachment by rivets or other equivalent fastening means 27 to the outer housing 3. The frusto-conical baffle and mixing section E discharges the material onto a discharge section F which includes a housing 29 which has its smaller end entering the discharge end of the baffle housing 23. The frusto-conical discharge housing 29 expands in the direction of flow of liquid and is provided with a multitude of holes 31. The large end of the housing 29 opens adjacent to the discharge end of the housing 3.

The housing 29 is mounted in the housing 3 by means of spaced webs 33 having flanges 35, 37 for receiving fastening instrumentalities 39, 41, as shown. The discharge end 43 of the housing 3

is somewhat smaller than the remainder of the housing 3, the tapering portion 45 of the housing 3 serving as the attaching portion for the webs 33.

It will be apparent from the drawings that the housing A is open at both ends, and the intake section D receives the liquid from the nozzle. The nozzle B is provided with means 46 for discharging liquid from the nozzle either as a solid stream or as a cone depending upon the adjustment of the means 46 through actuation of the knurled adjusting ring 47. The intake section D, the baffle section E and the discharge section F are symmetrically disposed in the housing 3 and are in axial alignment so that a solid stream of liquid projected by the nozzle B passes uninterruptedly through the attachment A, as is indicated by the dotted lines on the drawing.

When the adjustment of the nozzle B is to project a conical discharge, as shown by dash-and-dot lines on Fig. 1, such conical discharge impinges against the conical periphery of the frusto-conical housing 23 and is reflected by the angularity of the slope thereof through the throat 51 and thence against the outside of the expanding discharge housing 29 of the discharge section F. The deflection of the material from the inner side of the housing 23 finely subdivides the conical discharge flow from the nozzle, and passage through the holes 31 further subdivides the particles of liquid, and a voluminous mechanical foam is produced, the passage of the liquid through and around the discharge housing 29 drawing air through the open intake end 53 of the housing 3 and causes such air to commingle with the liquid passing through the baffle housing 23 and around and into the perforated discharge housing 29, so that a copious volume of foam is projected from the auxiliary nozzle A.

It will be apparent that the specifically illustrated foam of the invention herein shown and described is intended to be an illustrative form of the present construction, structural details of which may be modified without departing from the invention; and accordingly, it will be understood and desired to embrace within the scope of this invention such modifications and changes as may be necessary to adapt it to varying conditions and uses as defined by the appended claims.

Having thus described our invention, what we claim as new and wish to secure by Letters Patent is:

1. Fire-fighting apparatus comprising an auxiliary nozzle adapted to be mounted on a main nozzle adapted to deliver selected types of discharge streams of fire-extinguishing liquid from a solid stream to a conical stream, the said auxiliary nozzle comprising an outer housing open at both ends, one of the ends being an intake end and the opposite end a discharge end, a plurality of symmetrically disposed sections in the housing in communication one with another, there being an intake section, a baffle and mixing section and a discharge section, each of the sections opening into an adjacent section, the intake section being a substantially cylindrical housing defining an annular air space intermediate itself and the outer housing, the mixing section being a first frusto-conical housing converging towards the discharge end of the outer housing and having its larger end secured directly to the outer housing, the discharge section being a second frusto-conical housing diverging towards the discharge end of the outer housing, and having its smaller end extending into the smaller end of

the first frusto-conical housing, the intake housing and first and second frusto-conical housings being in relative alignment with one another and with the main nozzle for permitting the main nozzle to project a solid stream of liquid uninterruptedly through the housings and out of the discharge opening of the outer housing, while a conical stream of liquid projected from the nozzle impinges against the first frusto-conical housing and is subdivided thereby and mixed with air entering the intake end of the outer housing, the resulting mixture being directed by the converging housing into and around the diverging frusto-conical discharge housing and thence as a mechanical foam from the outer housing.

2. Fire-fighting apparatus comprising an auxiliary nozzle adapted to be mounted on a main nozzle adapted to deliver selected types of discharge streams of fire-extinguishing liquid from a solid stream to a conical stream, the said auxiliary nozzle comprising an outer housing open at both ends, one of the ends being an intake end and the opposite end a discharge end, a plurality of symmetrically disposed sections in the housing in successive communication one with another, there being an intake section, a baffle and mixing section and a discharge section, the intake section including a substantially cylindrical housing defining an annular air space with the outer housing, means securing the cylindrical housing concentrically in the outer housing, a frusto-conical mixing housing converging towards the discharge end of the outer housing and having its larger end concentrically disposed around the cylindrical intake housing, means directly securing the larger end of the mixing housing directly to the outer housing, a diverging frusto-conical discharge housing, and having its larger end disposed concentrically relative to the outer housing adjacent to the discharge end thereof, means for mounting the said frusto-conical discharge housing in the outer housing in alignment with the mixing housing and with the cylindrical intake housing, whereby a solid stream of liquid projected from the main nozzle can pass uninterruptedly through the series of housings and out through the discharge end of the outer housing, the frusto-conical discharge housing being provided with a multitude of holes therethrough, conical streams of liquid projected from the main nozzle impinging against the frusto-conical mixing housing and thereby becoming mixed with air drawn through the open intake end of the outer housing, and becoming converted into mechanical foam in and around the frusto-conical discharge housing.

3. An auxiliary nozzle adapted to be mounted on a principal nozzle of a fire-fighting hose, the main nozzle being adapted to deliver a solid stream of fire-fighting liquid and a conical stream thereof selectively, the auxiliary nozzle comprising a housing and a plurality of mixing sections in the housing, the said sections being disposed in axial alignment and having axially disposed openings therethrough adapted to pass uninterruptedly a solid stream of liquid delivered by the principal nozzle, the sections having angularly disposed sides adapted to be impinged by the conical stream from the said nozzle for converting the liquid of the stream into a foam.

4. An auxiliary nozzle adapted to be mounted on a principal nozzle of a fire-fighting hose, the main nozzle being adapted to deliver a solid stream of fire-fighting liquid and a diverging stream thereof, selectively, the auxiliary nozzle

comprising a housing open at opposite ends, one of the said ends being the intake end, the opposite end being the discharge end, a series of concentric baffle members mounted in the housing, and having aligned openings therethrough for delivering uninterruptedly a solid stream of liquid from the main nozzle, the said baffle members having axially concentric walls sloping in opposite directions adapted to be impinged by a diverging stream of liquid delivered by the principal nozzle, for dividing the said diverging stream into a mechanical foam in the presence of air aspirated into the baffle sections through the intake end of the housing.

5. An auxiliary nozzle adapted to be mounted on a principal nozzle of a fire-fighting hose, the main nozzle being adapted to deliver a solid stream of fire-fighting liquid and a diverging stream thereof selectively, the auxiliary nozzle comprising a housing open at opposite ends, one of the said ends being the intake end and the opposite end being the discharge end, a series of communicating concentric baffle members mounted on the housing and having aligned openings therethrough for delivering uninterruptedly a solid stream of liquid from the main nozzle, one of the baffle members having an inwardly converging conical baffle wall interposed in a diverging stream of liquid projected by the nozzle and converging towards the discharge end of the 30 housing, a second baffle member adjacent to the aforesaid baffle member and internally concentric therewith, the second baffle member having a conical baffle wall diverging or expanding towards the discharge end of the housing and being provided with a multiplicity of openings in the said expanding wall thereof, the baffle members converting the diverging stream into a mechanical foam in presence of air aspirated into the stream through the intake end of the housing.

6. An auxiliary nozzle adapted to be mounted

on a principal nozzle of a fire-fighting hose, the main nozzle being adapted to deliver a solid stream of fire-fighting liquid and an expanding stream thereof selectively, the auxiliary nozzle comprising a housing open at opposite ends, one of the said ends being the intake end and the opposite end the discharge end, and a mechanical foam-producing chamber in the housing, the chamber having a section converging towards the discharge end of the housing and a section diverging towards the discharge end of the housing, the said chamber presenting a continuous fluid passage aligned with the main nozzle for allowing a solid stream from the nozzle to pass uninterruptedly through the housing from the intake end to the discharge end, the converging section having walls positioned in the path of the expanding discharge from the principal nozzle for subdividing the expanding discharge into mechanical foam, in the presence of air aspirated through the intake end of the housing, the diverging section of the mechanical foam-producing chamber having a multitude of openings through its walls for further mixing and subdividing foam and air.
